Primary Examiner — Rhea Shields(74) *Attorney, Agent, or Firm* — Seed IP Law Group LLP(57) **CLAIM**

The ornamental design for an electrical plug connector, as shown and described.

DESCRIPTION

1.1 is a perspective view of an electrical plug connector, showing our new design.

1.2 is a left side view thereof.

1.3 is a front view thereof.

1.4 is a right side view thereof.

1.5 is a back view thereof.

1.6 is a top view thereof.

1.7 is a bottom view thereof.

In the drawings, the broken lines are for the purpose of illustrating environment only and form no part of the claimed design.

1 Claim, 7 Drawing Sheets(56)
